(57) **CLAIM**

The ornamental design for an awning, as shown and described.

DESCRIPTION

FIG. 1 is a front, right perspective view of an awning in accordance with the present invention;

FIG. 2 is a right side, elevation view thereof;

FIG. 3 is a front, elevation view thereof;

FIG. 4 is a top, elevation view thereof;

FIG. 5 is a left side, elevation view thereof; and,

FIG. 6 is a rear, elevation view thereof.

The broken lines showing a possible portable shelter to which the awning of the present invention is attached is for illustrative purposes only and forms no part of the claimed design.
